FOLDING AND NONFOLDING MARINE CRAFT

Charles Haskell Clark, San Francisco, Calif., assignor, by mesne assignments, of one-half to Paul F. Schumacher, San Francisco, Calif.

Application April 23, 1940, Serial No. 331,150

15 Claims. (Cl. 9—2)

The invention, in general, relates to relatively light-weight boats which are nevertheless sufficiently rugged to withstand heavy duty. The present invention constitutes an improvement of the marine craft of my invention disclosed and claimed in Letters Patent No. 2,111,555, granted to me on March 22, 1938, and reissued April 29, 1941, as Reissue No. 21,787, and this application is a continuation-in-part of my co-pending application entitled "Folding and non-folding marine craft," filed September 23, 1939, and bearing Serial No. 296,263, now Patent Number 2,243,247.

A primary object of the present invention is to provide improved, inexpensive row boats and motor boats both of the folding and rigid types which are relatively inexpensive and simple to construct.

Another object of my invention is to provide craft of the above mentioned nature which are characterized by an improved bow insuring smoother movement of the craft through the water.

A still further object of the invention is to provide folding rowboats and motor boats which can be set up and collapsed in a comparatively short time and which, when folded, take up a minimum of space.

Another object of the invention is to provide marine craft of the indicated nature which are sturdy and have maximum stability for given widths and lengths of the craft.

Other objects of the invention, together with some of the advantageous features thereof, will appear from the following description of a preferred embodiment of my present improvement, as exemplified in row-boats and motor boats. It is to be understood that I am not to be limited to the precise embodiment shown, as the invention, as defined in the appended claims, can be embodied in a plurality and variety of forms.

Referring to the drawings:

Figure 1 is a plan view of a preferred embodiment of the invention, as exemplified in a row boat and as set up for use in the water; this view omitting the inner protection strips at the flexible joints for the sake of clarity.

Figure 2 is a longitudinal sectional view of the embodiment illustrated in Figure 1; this view omitting the inner protection strips for purposes of clarity.

Figure 3 is a side elevation of the embodiment of my invention shown in Figure 1.

Figure 4 is a side elevation of the embodiment of Figure 1 but in folded condition after the stern

panel and seat have been removed, the dotted lines indicating the shape of the side sheets and the full lines the shape of the bottom sheets of the craft.

5 Figure 5 is a fragmentary side view of the stern of the row boat, the view being partly in section to illustrate the folding character of the flexible fabric covering the interior surface of the stern panel.

Figure 6 is an elevational view of the stern panel of the craft of my present invention, as exemplified in a row boat.

Figure 15 is a view taken on the section line 45 15—15 of Figure 12.

Figure 16 is a side elevation of a preferred embodiment of my invention, as exemplified in a folding motor boat; this view showing the craft with the stern panel and seats removed and in folded condition, the dotted line showing indicating the shape of the side sheets and the full line showing indicating the shape of the bottom sheets of the craft.

Figure 17 is a view taken on the line 50 17—17 of Figure 16; this view omitting the inner pro-

tection strips at the flexible joints for purposes of clarity.

Figure 18 is a perspective view of the stern panel of the motor boat exemplification of the present invention.

Figure 19 is a fragmentary perspective view of the stern of the motor boat exemplification of my invention, this view showing the stern panel removed.

In its preferred embodiment, the present invention as exemplified in a folding row boat preferably comprises a hull formed to two symmetrical sections including a pair of bendable bottom sheets, means flexibly joining said bottom sheets together at their inner lateral edges, a pair of bendable side sheets, and means flexibly joining each side sheet to a bottom sheet; each of said bottom sheets having a lateral inner edge which is substantially straight for a major portion of its length and which is slightly curved at one extremity and excessively curved at the other extremity, and having an outer lateral edge which is longitudinally convex from one end of the sheet to a point adjacent the other end, said outer lateral edge of each bottom sheet having an off-set portion extending from said point and a diagonal portion extending from said off-set portion to the adjacent end of the sheet; each of said side sheets having an inner lateral edge which is longitudinally convex and equal in length to the convex portion of the outer lateral edge of a bottom sheet, each side sheet also having a diagonal end equal in length and extending in the same direction as the off-set portion of the outer lateral edge of a bottom sheet, and each side sheet having a straight outer lateral edge, together with means disposable in said hull for spreading said bottom sheets apart and for longitudinally twisting said bottom sheets, said means also effecting an outward bowing of said bottom sheets both laterally and longitudinally adjacent the bow of the boat, and a stern panel detachably fastened to said bottom and side sheets and transversely spanning the hull.

In its preferred form, the improvement of my present invention, as exemplified in a folding motor boat preferably comprises a hull formed to two symmetrical sections including a pair of bendable bottom sheets, means flexibly joining said bottom sheets together at their inner lateral edges, a pair of bendable side sheets, means flexibly joining each of said side sheets to a bottom sheet; each of said bottom sheets having an inner lateral edge which is substantially straight for a major portion of its length and excessively curved at one extremity, and having a straight outer edge with a slight off-set portion adjacent one extremity and a diagonal portion extending from the off-set portion to the end of the sheet; each of said side sheets having a straight inner lateral edge equal in length to the outer lateral edge of each bottom sheet, and each side sheet having a diagonal end equal in length to the length of the off-set portion of the outer lateral edge of each bottom sheet, said side sheets each having a straight outer lateral edge, together with means removably disposable in the hull for longitudinally twisting said bottom sheets; and a stern panel detachably fastened to said side and bottom sheets and transversely spanning the hull.

The rigid or non-folding boats of the present improvement, as exemplified in row boats and

motor boats, are similar to the folding boats with the exception that the rigid craft are provided with continuous gunwale strips spanning the offset provided adjacent one end of the bottom panel.

In accordance with my present invention, as exemplified in a folding row boat, I provide a hull which includes two bendable bottom sheets 11 and 12, a pair of bendable side sheets 13 and 14, and a stern panel 15. The two bottom sheets 11 and 12 are identical in shape and dimensions and, likewise, the two side sheets 13 and 14 are identical in shape and dimensions so that there is provided a hull which, when the craft is set up for use in the water, consists of two symmetrical sections as clearly depicted in Figure 1 of the drawings. The sheets 11 to 14 inclusive, preferably are cut from plywood, although any other suitable bendable material, such as water-pressed paper, galvanized iron or other sheet metal, may be used, as desired. Sheets 11 and 12 are flexibly joined together on a longitudinal medial line of the hull and side sheets 13 and 14 are flexibly joined to the bottom sheets defining main fold lines of the craft. To this end, I preferably utilize opposed strips 16 and 17 of water-impervious canvas for flexibly connecting bottom sheets 11 and 12 together along the keel line and four canvas strips 18, 19, 20 and 21 for hingedly connecting each side sheet to a bottom sheet. See Figure 9 of the drawings. Interior strips 16, 18 and 20 are preferably joined to the interior surfaces of the sheets by glue layers 22 and 23 for strip 16, layers 31 and 32 for strip 18, and layers 41 and 42 for strip 20, as these strips are not constantly subjected to water. Inner protection strips 24 and 25 of wood or metal are applied over the edges of strip 16, inner protection strips 33 and 34 over the edges of strip 18, and inner protection strips 43 and 44 over the edges of strip 20. While the inner protection strips 24, 25, 33, 34, 43 and 44 are shown in the drawings as relatively thick, they are thus shown only for purposes of illustration but in actual practice such strips are flat or relatively thin and in no way interfere with the folding of the panels together when collapsing the craft since such panels are resilient. Outer strips 17, 19 and 21 however, are subject to constant immersion and therefore I prefer to join strips 17, 19 and 21 to the sheets by the use of water proof layers, preferably formed by saturating a carrier or bonding strip with asphalt emulsion, which may be applied to the sheets and allowed to solidify before the strips 17, 19 and 21 are placed thereon. Thus carrier strips 26 and 27 are placed beneath strip 17, carrier strips 36 and 37 beneath strip 19, and carrier strips 46 and 47 beneath strip 21. Strips 17, 19 and 21 are then placed over the carrier strips; strip 17 being forced into intimate contact underneath with the carried emulsion by fastening keel strips of wood or metal 28 and 29 over strip 17. Likewise exterior protection strips 38 and 39 are used to force canvas strip 19 against the carrier strips 36 and 37, and protection strips 48 and 49 are used for the same purpose for attaching canvas strip 21. Thus all exterior canvas strips are provided with waterproof attachments as the asphalt flows under the pressure of the protection strips and bonds the canvas to the sheets.

In order to prevent accumulation of moisture that might penetrate the joint and otherwise damage the same, I preferably slit the inner

strip 46 transversely at spaced intervals throughout its length, as indicated by the reference numeral 30, see Figure 1 of the drawings. The central portions of strips 18 and 19, as well as the central portions of the canvas strips 20 and 21, are stitched throughout their length in order to avoid pulling the strips from the sheets. It is also to be noted that I preferably slit the inner strips 18 and 20 transversely and at spaced intervals throughout their lengths, as indicated at 50 in Figures 1 and 2 of the drawings, in order to prevent accumulation of water that may penetrate the joint and force the glued strips 16, 18 and 20 away from the surface of the panel to which they are glued when the craft is folded. As particularly shown in Figures 2 and 4 of the drawings, each bottom sheet is so formed as to provide thereon an outer lateral edge 52 which is longitudinally convex from one end to a point adjacent to its other end, as indicated by reference numeral 54, at which point, the outer lateral edge 52 of the bottom sheets is provided with an off-set portion 56 from which the edge extends diagonally, as at 57, to the adjacent end of the sheet. Each of the side sheets 13 and 14 of the folding row boat is so formed as to provide thereon an inner lateral edge 58 which is equal to the length of the convex portion 54 of the outer lateral edge of the bottom sheets and likewise which has the same degree of convexity as the outer lateral edge of the bottom sheets. Moreover, each side sheet is so formed as to provide thereon a diagonal end 59 which is equal in length to the offset portion 56 of the bottom sheets.

A floor-board 64 is provided with means for detachably fastening the same in the hull, the fastening means being shown in enlarged detail in Figure 7 of the drawings. As shown in Figure 1, I provide two strips 66 and 67 which are fastened 40 to the inner surfaces of the bottom sheets 11 and 12 at opposite sides and at equal distances from their inner lateral edges. The strips 66 and 67 are provided at spaced intervals with plates 68, arranged in opposed pairs, in each of which an aperture 69 is formed. The strips 66 and 67 are provided with recesses 71 below the apertures 69 of each plate 68, and the apertures and recesses together serve to receive tongues 72 carried by strips 73 fastened to the under side of the floor-board 64. By these means the floor-board can readily be installed in the hull and as readily removed therefrom, as it is only necessary to fit the tongues 72 of the strips 73 into the holes formed by the apertures 69 of plates 68 and recesses 71 of the strips 66 and 67.

The support for the removable seat preferably includes an upright 77 which is fitted into a recess formed in the floor-board 64, the upright being slotted for receiving a panel 78 which is firmly but detachably secured to upright 77 by means of screw-bolts 79 which pass through the upright and the panel, as shown in Figure 2 of the drawings. Panel 78 transversely spans the hull and has an upright extension 71' at each end which bears against and is secured to the side panels by a bolt 78' passing through the side panel from the outside and secured by wing nut 79'. A two-part seat 81, which is foldable by virtue of the provision of hinges 82 connecting the same, rests upon the panel 78 and is additionally supported at each end, upon the gunwale of the craft by any suitable suspending means, such as short chains 83 and the clamps 84 as well as clamp 86 attached to the seat by

bolt and wing nut 87 having arms for engaging the side sheets at their outer lateral edges, or the gunwale of the craft. In addition to seat 81, I also provide a removable seat 88 at the stern of the craft which conveniently is suspended by suitable brackets 89, bolts and wing nuts 90. It is apparent that the seat 88 likewise is readily installed and removed from the craft.

In accordance with the present invention, as exemplified in a folding row-boat, a flexible connection is provided between the side and bottom sheets at the stern of the craft in order to facilitate the folding of the boat after the stern panel 15, as well as the floor-board, seats 81 and 88 have been removed. Preferably, I employ a sheet of water-proof canvas 91 for effecting this flexible connection, the sheet 91 extending from top to bottom of the hull, and transversely thereof, to entirely close the stern of the craft when set up. Any suitable means, such as adhesive, nails or rivets, can be employed for fastening the canvas sheet 91 in operative position. It is clear that when the craft is set up and in use in the water, the canvas sheet 91 is in a tautened condition. However, when the craft is folded the canvas sheet 91 also is simultaneously collapsed, as indicated by the showing of Figure 5 of the drawings. It is to be particularly observed that the canvas sheet 91 is fastened inside of the stern panel and interiorly faces the same. Any suitable means can be employed for detachably fastening stern panel 15 in position. To this end, I provide in the embodiment of folding row boat illustrated, metal clamps 92 on the stern panel, all clamps being apertured for passing bolts 93 which pierce the side sheets and receive wing nuts 94 for tightening the clamps in position. In addition to the clamps 92 on the stern panel, the side sheets 13 and 14 at the stern of the craft are provided with angle clamps 95 adjacent the bottom of the hull and, in mounting the stern panel, the legs of the clamps 95 are engaged by the panel so as to bring the stern panel into contact with the ends of the side and bottom sheets prior to screwing down the wing nuts 94 to tighten the clamps 92.

Suitable oar-locks 96 of standard construction are removably mounted on the gunwale of the craft in opposed pairs and at desired intervals 50 along the gunwale, the attaching means for the oar-locks 96 conveniently consisting of clamps 97, together with screw bolts and wing nuts. It is clear that the positioning of the oar-locks in opposed pairs on the gunwale of the craft can be varied to suit the requirements of the particular user of the craft.

While it is not essential, I provide reinforcing strips 98 at the bow of the craft, these strips being arranged in transverse pairs and fastened to the inner surfaces of the bottom sheets 11 and 12. Moreover, I also provide a hinge 99 at the bow of the craft to facilitate folding at this point when collapsing the hull, the hinge conveniently having extensions 100 thereon to reinforce the bow further, although this is not essential.

In the row boat exemplification of the present improvement, gunwale strips are provided to strengthen the side sheets at their outer lateral edges and also to provide an attractive finishing to the craft. In the folding exemplifications, two gunwale strips are provided for each side of the hull, as clearly shown in Figure 1 of the drawings. On one side, a relatively long gunwale strip 101 is fastened to the side panel 14

adjacent its outer lateral edge, strip 101 extending the full length of the side sheet, and a relatively short gunwale strip 102 is fastened to the bottom sheet 12 adjacent to the diagonal portion 57 of its outer lateral edge. Similarly, I fasten a relatively long gunwale strip 103 to the side sheet 13 adjacent to its lateral outer edge and also fasten a relatively short gunwale strip 104 to the bottom sheet 11 adjacent to the diagonal portion 57 of its outer lateral edge. In the non-folding or rigid exemplifications of the row boat, continuous gunwale strips are fastened adjacent the outer lateral edges of the side and bottom sheets and extend the full length of the craft on both sides of the hull.

In Figures 11 to 19, inclusive, I have depicted an embodiment of the present invention as exemplified in a folding motor boat, and it is to be observed that this exemplification likewise is provided with a life-boat bow as in the case of the folding row boat. In describing the structure of this modification parts having functions common to both embodiments are numbered with the last two digits corresponding to the numbers of the related parts in the first embodiment described. The folding motor boat likewise comprises a hull, formed to two symmetrical sections including a pair of bendable bottom sheets 111 and 112, and a pair of bendable side sheets 113 and 114 all cut preferably from plywood although any other suitable bendable material can be employed for fabricating the bottom and side sheets, such as a waterproof pressed paper or a bendable metal such as galvanized iron. The stern of the craft is closed with a stern panel 115 which, as more particularly described hereinafter, functions to flatten out the stern of the craft. As in the case of the folding row boat exemplification, the two bottom sheets 111 and 112 of the folding motor boat are flexibly connected together on a longitudinal medial line of the craft preferably by means of two canvas strips 116 and 117 which are fastened interiorly and exteriorly of the hull, respectively. Moreover, each side sheet is flexibly connected to a bottom sheet forming main fold lines on each side of the craft. As shown, side sheet 113 is flexibly connected to the bottom sheet 111 interiorly and exteriorly of the hull by means of canvas strips 118 and 119, respectively, while side sheet 114 is flexibly connected to the bottom sheet 112 interiorly and exteriorly of the hull by means of the canvas strips 120 and 121, respectively, see Figure 15 of the drawings.

The flexible connections are preferably formed as outlined above in the description of my first embodiment. Thus, I provide inner protection strips 124 and 125 of relatively thin wood or metal which are applied over the edges of strip 116; also inner protection strips 133 and 134 over the edges of strip 118; and inner protection strips 143 and 144 over the edges of strip 120. Likewise, carrier strips 126 and 127 which are saturated with an asphalt emulsion are placed beneath outer strip 117; also carrier strips 136 and 137 are placed beneath strip 119; and carrier strips 146 and 147 beneath strip 121. Moreover, keels 128 and 129, of wood or metal, are fastened over outer strip 117. Likewise, exterior protection strips 138 and 139 are used to force canvas strip 119 against the carrier strips 136 and 137, and protection strips 148 and 149 are used for the same purpose for attaching canvas strip 121. These inner protection strips 124, 125, 133, 134 and 143, 144 are, in practice, so flat or

thin that no interference with the folding of the panels of the craft together is had.

As particularly illustrated in Figures 12 and 16 of the drawings, the two bottom sheets 111 and 112 are cut to the same shape and dimensions, and the two side sheets 113 and 114 likewise are cut to the same shape and dimensions in order that symmetrical sections are provided when the craft is set up for use in the water. Preferably, each bottom sheet is so formed as to provide thereon an inner lateral edge having a substantially straight portion 151 nearly co-extensive with its length and having one excessively curved extremity 153. Moreover, each bottom sheet is so cut as to provide thereon an outer lateral edge having a portion 154 which is on a bias from one end of the sheet to a point adjacent the other end, said edge having a slight offset portion 156 as well as a short diagonal portion 157 extending from the offset portion 156 to the end of the sheet, where it meets the end of the curved extremity 153 of the inner lateral edge of the sheet. Each of the side sheets of the folding motor boat exemplification of the present invention preferably is so formed as to provide thereon an inner lateral edge 158 which is cut on the same bias as the portion 154 of the outer lateral edge of a bottom sheet and equal in length thereto, each of the side sheets having a short diagonal end 159 which is equal in length to the slight offset portion 156 of the bottom sheets. Moreover, each of the side sheets is so cut as to provide thereon an outer lateral edge 161 which is substantially straight for its entire length but slightly curved at the bow extremity of the craft, as indicated by reference numeral 163 in Figure 12 of the drawings.

In accordance with the present invention, I provide means disposable in the hull of the craft for effecting the setting up of the craft for use in the water and for simultaneously longitudinally twisting each bottom sheet from its longitudinal center outwardly to its extremities to afford a life-boat bow for the craft. These means preferably also effect a slight bowing of the bottom sheets, both laterally and longitudinally adjacent the bow end of the craft. The means that I preferably employ are similar to the means utilized for the same purpose in the folding row boat exemplification and include a floor board 164 which is adapted to be removably disposed in the bottom of the hull. Preferably, I detachably fasten the floor board in the hull by employing two longitudinally extending strips 166 and 167 which are secured to the inner surfaces of the bottom sheets 111 and 112 on opposite sides and at equal distances from their inner lateral edges. As in the case of the folding row boat, the strips 166 and 167 carry plates 168 arranged in opposed pairs at intervals along the strips, the plates 168 being apertured and the strips 166 and 167 being recessed below the apertures of the plates to provide holes for the reception of tongues 172 carried on metal strips 173 fastened to the under side of the floor board 164. The floor board conveniently is cut away at suitable places, as at 174, to form foot rests for the users of the craft, see Figure 11 of the drawings. It is clear that placement of the floor board in operative position in the hull is a relatively simple matter since all that is necessary is to fit the tongues 172 of strips 173 into the holes, as above described, and slip the floor board in place. At the longitudinal center of the craft, the bottom sheets 111 and 112 are so spread that

they will lie at an angle approximately 70° away from a vertical line through the exact center of the craft.

As illustrated particularly in Figures 11 and 12 I provide center, front and rear seats for the motor boat, together with suitable supporting means therefor so that the several seats can be removably disposed in the hull rapidly and easily. The support for the center seat preferably includes an upright 177 which is fitted into a recess or aperture formed in the floor board 164 and which is slotted to receive a panel 178. The panel 178 is firmly but detachably fastened to upright 177 by means of screw bolts 179 and transversely spans the hull with its lateral edges bearing against the inner surfaces of the side and bottom sheets maintaining the same in a spread apart condition. As shown, a center seat 181 is provided and rests on the panel 178 and is additionally supported on the gunwale of the craft by means of suitable brackets 186, screws and wing-nuts 187. While a one piece seat is shown, the seat 181 may be constructed of two pieces hingedly connected together, if desired. The boat is held in shape during use by the center seat 181 and supporting member 178. At the stern of the craft, I provide a removable seat 188 which conveniently is suspended on the gunwale of the craft by suitable clamps 189, bolts and wing nuts 190. Preferably, the clamps 189 carry a short pin 180, as shown in Figure 14 of the drawings, so that when the seat is installed in the hull the head of each pin 180 is received on the hole of a small washer 185 secured to the inner surface of the side panel. To remove seat 188, side sheets 113 and 114 are sprung apart sufficiently to allow the heads of pins 180 to slip out of the washer openings. Similar means can be employed for fastening the center seat 181 in position. In addition to seats at the center and stern of the craft, I also provide a removable seat 181a for disposal adjacent the bow of the hull, together with means for detachably fastening the same in position. To this end, I provide an upright panel 178a which transversely spans the hull and which is notched at the bottom for cooperating with a small, upstanding extension on floor board 164, as shown in Figure 12 of the drawings. The panel 178a carries a small clamp 177a, one leg of which fits under the end of floor board 164 when the panel 178a is fitted into engagement with the floor board. Preferably, the clamp 177a is detachably secured to the panel 178a by means of screw bolts 179a. The seat 181a preferably is hingedly fastened to panel 178a and to this end a hinge 175a is fastened to the upper end of panel 178a as well as to the seat 181a so that the panel partially supports the seat. At the other lateral edge of seat 181a and at each side thereof, I provide a pair of clamps 186a for removably supporting the seat 181a within the craft, clamps 186a being rigidly fastened to the side sheets by means of suitable bolts and wing nuts 187a. Thus I have provided a boat having a substantially rectangular stern upon which, if desired an outboard motor may be mounted, this rectangular stern providing a substantially flat bottom at the rear of the boat, as is desirable in motor boat design.

I claim:

1. A marine craft comprising a hull including a pair of bendable bottom sheets and a pair of bendable side sheets, each of said bottom sheets having a longitudinally convex outer lateral edge, and an inner lateral edge which is curved at one extremity and substantially straight at its other

extremity, and each of said side sheets having a longitudinally convex inner lateral edge, means joining said bottom sheets on a longitudinal medial line of the craft at their inner lateral edges, means joining each side sheet to a bottom sheet at their inner and outer lateral edges respectively, said bottom sheets being adapted to be longitudinally twisted when the craft is set up for use in the water, means in said hull bearing against the inner surfaces of said bottom sheets at opposite sides of the hull; said means being of such dimensions as to maintain said bottom sheets spread apart and to maintain the twist in said bottom sheets whereby the longitudinal extremities of said bottom sheets lie in substantially the same plane as the adjacent extremities of said connected side sheets at the bow of the craft, and flexible means closing the stern of the craft.

2. In a marine craft having a pair of sheets having opposed edges, waterproof means for joining said sheets comprising an inner flexible strip extending across said edges and bonded to the inner surfaces of said sheets adjacent said edges, a bonding strip applied to each of said sheets along the outer surface of each sheet and impregnated with a semi-solid waterproof bonding material, an outer flexible strip extending across said edges over both of said bonding strips and longitudinal rigid strip means applied to said outer flexible strip over each of said bonding strips and secured to said sheets under pressure to bond said outer strip to said sheets with said bonding strips therebetween.

3. In a marine craft having a pair of sheets having opposed edges, water-proof means for joining said sheets comprising an inner flexible strip extending across said edges and bonded to the inner surfaces of said sheets adjacent said edges, a bonding strip applied to each of said sheets along the outer surface of each sheet and impregnated with a semi-solid water-proof bonding material, an outer flexible strip extending across said edges over both of said bonding strips, and longitudinal rigid strip means applied to said outer flexible strip over each of said bonding strips and secured to said sheets under pressure to bond said outer strip to said sheets with said bonding strips therebetween; said inner flexible strip being slit at spaced intervals to prevent water retention between inner and outer flexible strips.

4. Means for joining cloth to a rigid boat member to form a waterproof joint comprising a bonding strip impregnated with a bonding material such as asphalt emulsion applied to said member, a cloth applied to said bonding strip and means for forcing said cloth against said bonding strip and said member.

5. A marine craft comprising a hull including a pair of bottom sheets, each of said bottom sheets having a substantially straight outer edge and joined bottom edges substantially straight over the major portion thereof curving to meet the outer edges thereof at the bow of said hull, and a pair of triangular side sheets each joined along one edge thereof to an outer edge of one of said bottom sheets, the apex ends of said side sheets terminating adjacent the bow ends of said bottom sheets, the basal ends of said side sheets terminating in the plane of the stern ends of said bottom sheets and means for spreading said sheets to form and maintain said sheets into a hull having a rectangular stern and a life boat bow.

6. A marine craft comprising a hull including a pair of bottom sheets each of said bottom sheets having a substantially straight outer edge and

joined bottom edges substantially straight over the major portion thereof curving to meet the outer edges thereof at the bow of said hull, and a pair of triangular side sheets each joined along one edge thereof to an outer edge of one of said bottom sheets, the apex ends of said side sheets terminating adjacent the bow ends of said bottom sheets, the basal ends of said side sheets terminating in the plane of the stern ends of said bottom sheets, and flexible means attached to said sheets at the stern end thereof to form a hull closure.

7. A marine craft comprising a hull including a pair of bottom sheets, each of said bottom sheets having a substantially straight outer edge and joined bottom edges substantially straight over the major portion thereof curving to meet the outer edges thereof at the bow of said hull, and a pair of triangular side sheets each joined along one edge thereof to an outer edge of one of said bottom sheets, the apex ends of said side sheets terminating adjacent the bow ends of said bottom sheets, the basal ends of said side sheets terminating in the plane of the stern ends of said bottom sheets, flexible means attached to said sheets at the stern end thereof to form a hull closure and a rigid stern closure adjacent and outside of said flexible closure.

8. A foldable marine craft comprising a hull formed of two symmetrical sections including a pair of bendable bottom sheets, means flexibly joining said bottom sheets together at their inner lateral edges, a pair of bendable side sheets, means flexibly joining each side sheet to a bottom sheet at the outer lateral edges of said bottom sheets; each of said bottom sheets having an inner lateral edge which is substantially straight for a major portion of its length but which is slightly curved at one extremity and excessively curved at the other extremity, and having an outer lateral edge which is longitudinally convex from one end of the sheet to a point adjacent the other end thereof, said outer lateral edge of each bottom sheet having an off-set portion extending from said point and a diagonal portion extending from said off-set portion to the adjacent end of the sheet; each of said side sheets having an inner lateral edge which is longitudinally convex and equal in length to the convex portion of the outer lateral edge of each bottom sheet, each side sheet also having a diagonal end equal in length and extending in the same direction as the off-set portion of the outer lateral edge of each bottom sheet, and each side sheet having an outer lateral edge which is substantially straight throughout its length, said bottom sheets being adapted to be twisted longitudinally when setting up the craft for use in the water, means in the hull bearing against the inner surfaces of said bottom sheets for holding said bottom sheets spread apart and for maintaining the twist therein, said means being of such extent and said bottom sheets being of such shape as to afford an outward bowing of said bottom sheets both laterally and longitudinally adjacent the bow of the hull, and a stern panel detachably fastened to said bottom and side sheets and transversely spanning the hull.

9. In a marine craft, a hull formed of two symmetrical sections and comprising a pair of bendable bottom sheets and a pair of bendable side sheets, means flexibly connecting said bottom sheets together at their inner lateral edges, and means flexibly connecting each side sheet to a bottom sheet at the lateral outer edge of each bottom sheet; each of said bottom sheets hav-

ing an inner lateral edge which is substantially straight for a major portion of its length but which is slightly curved at one extremity and excessively curved at the other extremity, and having an outer lateral edge which is longitudinally convex from one end to a point adjacent the other end thereof, said outer lateral edge of each bottom sheet having an off-set portion extending from said point and a diagonal portion extending from said off-set portion to the adjacent end of the sheet; each of said side sheets having an inner lateral edge which is longitudinally convex and equal in length to the convex portion of the outer lateral edge of each bottom sheet, each side sheet also having a diagonal end equal in length and extending in the same direction as the off-set portion of each bottom sheet and each side sheet having a straight outer lateral edge.

10. In a marine craft including a pair of sheets having opposed edges, water-proof means joining said sheets at said edges comprising a bonding strip impregnated with a semi-solid, water-proof material and applied to each of said sheets adjacent to said edges, a flexible strip extending across said edges and bonded to the outer surfaces of said bonding strips, and a pair of outer rigid strips secured to and exerting pressure upon said flexible strip on each of said sheets adjacent to said edges to firmly bond said flexible strips and said bonding strip together.

11. A foldable marine craft comprising a hull formed of two symmetrical sections and including a pair of bendable bottom sheets, means flexibly joining said bottom sheets together at their inner lateral edges, a pair of bendable side sheets, means flexibly joining each side sheet to a bottom sheet at an outer lateral edge thereof; each of said bottom sheets having an inner lateral edge which is substantially straight throughout its entire length except that it is excessively curved at one extremity, and having a straight outer lateral edge with a slight off-set portion adjacent one extremity and a diagonal portion extending from the off-set portion to the adjacent end of the sheet; each of said side sheets having a straight inner lateral edge equal in length to the outer lateral edge of said bottom sheet, and each side sheet having a diagonal end equal in length to the off-set portion of the outer lateral edge of each bottom sheet, said side sheets each having a straight outer lateral edge, said bottom sheets being adapted to be longitudinally twisted in setting up the craft for use in the water, means in the hull bearing against the inner surfaces of said bottom sheets to maintain them spread apart and to maintain the longitudinal twist in said bottom sheets, and a stern panel detachably fastened to said side and bottom sheets and transversely spanning the hull.

12. In a marine craft, a hull formed of two symmetrical sections including a pair of bendable bottom sheets and a pair of bendable side sheets; each of said bottom sheets having a substantially straight outer lateral edge, and each of said side sheets having a substantially straight inner lateral edge, said bottom sheets being adapted to be longitudinally twisted, and means in said hull bearing against the inner surfaces of said bottom sheets for maintaining a longitudinal twist in each of said bottom sheets.

13. In a marine craft, a floor-board, a seat disposable in the craft adjacent to the bow thereof; said seat including a first panel transversely spanning the hull of the craft, and a seating panel hingedly fastened to said first panel, means

for removably supporting said seating panel within the craft, and means for detachably but rigidly securing said seat within the craft; said means including a notch formed in the bottom of said first panel, an extension projecting upwardly from said floor-board and fitting into said notch, and a two-legged clamp joining said first panel to said floor-board, one leg of said clamp engaging under the end of said floor-board and the other leg thereof being detachably fastened to said first panel.

14. A rigid or nonfolding marine craft comprising a hull formed of two symmetrical sections including a pair of bottom sheets, means flexibly joining said bottom sheets together at their inner lateral edges, a pair of side sheets, means flexibly joining each side sheet to a bottom sheet at the outer lateral edges of said bottom sheets; each of said bottom sheets having an inner lateral edge which is substantially straight for a major portion of its length but which is slightly curved at one extremity and excessively curved at the other extremity, and having an outer lateral edge which is longitudinally convex from one end of the sheet to a point adjacent the other end thereof, said outer lateral edge of each bottom sheet having an off-set portion extending from said point and a diagonal portion extending from said off-set portion to the adjacent end of the sheet; each of said side sheets having an inner lateral edge which is longitudinally convex and equal in length to the convex portion of the outer lateral edge of each bottom sheet, each side sheet also having a diagonal end equal in length and extending in the same direction as the off-set portion of the outer lateral edge of each bottom sheet, and each side sheet having an outer lateral edge which is substantially straight throughout its length; said bottom sheets being adapted to be twisted longitudinally, means in the hull for spreading the bottom sheets apart and for main-

5 taining the twist in said bottom sheets, and a pair of gunwale strips each fastened to a side sheet adjacent the outer lateral edge thereof as well as fastened to a portion of each bottom sheet which is contiguous to the end of the corresponding side sheet; said gunwale strips extending for the full length of the craft.
